UNITED STATES PATENT OFFICE.

CHARLES ALTMANN, OF LYONS, FRANCE.

STEAM-BOILER.

SPECIFICATION forming part of Letters Patent No. 653,372, dated July 10, 1900.

Application filed March 7, 1900. Serial No. 7,684. (No model.)

To all whom it may concern:

Be it known that I, CHARLES ALTMANN, a citizen of France, residing at Lyons, Rhône, France, have invented a new and useful 5 Steam-Boiler for Instantaneous Vaporization, of which the following is a full, clear, and exact description, and for which I have made applications for patents in France, dated July 21, 1899, and in Great Britain, dated August 10 9, 1899.

The boiler which forms the subject of my invention belongs to the class of instantaneous vaporizers with narrow channels.

It is the object of my invention to provide 15 a construction having a large heating-surface under a small volume and reducing the number of joints and couplings to a minimum, so as to allow an easy examination of the interior channels.

20 The annexed drawings show an embodiment of my invention.

Figure 1 is a vertical section passing through the axis of the boiler. Fig. 2 is a plan view, partly in section. Fig. 3 shows a diaphragm 25 of flexible material.

The boiler is essentially composed of two cylindrical rings of metal *a* and *b*, placed one in the other and leaving between them a very narrow space, forming a circular channel *c*.

30 A series of narrow recesses *d d*, made on the inner side of ring *a* and on the outer side of ring *b*, open into this channel and form, with the same, a very great heating-surface, in which the water can circulate and vaporize.

35 The two rings *a* and *b* are joined together by means of two annular plates *g f*, closing the narrow space *c* at the top and at the bottom. These plates are fixed by screws *e e*, entering into the thickness of the rings, so as to be

40 sheltered against the direct action of the fire. The boiler thus formed is submitted to the action of a furnace, which may be heated either with coals, gas, or mineral oils and which may be disposed so as to heat the free 45 surfaces of the rings either at the same time or successively. According to circumstances, the boiler may be enveloped with a fireproof material or with an annular reservoir, in

which the feed-water can be warmed before being introduced into the boiler. 50

The water brought by a pump penetrates into the boiler through a pipe *h*, placed at the lower part of same, and vaporizes in passing up through the narrow channels. The steam is collected in the upper part at two 55 opposite points of the circumference by a collector *k*, to which is secured an overheating-pipe plunging into the furnace. This overheating-pipe is formed of a hollow cylinder *j*, provided with grooves *i i* in the inside 60 wider than those of the vaporizer and in the center of which the steam-outlet pipe *l* is secured. The steam collected by the collector *k* descends into tube *j*, gets overheated in the grooves *i*, and goes through tube *l* to the place 65 where it is to be employed. Should the rings *a* and *b*, having a certain height, be unequally heated, the inconvenience of their unequal expansion may be avoided by forming the lower joint, Fig. 3, by means of a diaphragm 70 *m*, of flexible metal, held by two rings or plates *f f*.

The height and diameter of the rings *a* and *b* depend on the quantity of steam that is to be produced and the kind of heating that is 75 to be employed; but the breadth of channel *c* and of the grooves *d* must never exceed the limits beyond which a spheroidal state might produce itself.

Having fully described my invention, what 80 I claim, and desire to secure by Letters Patent, is—

1. A boiler comprising an inner and outer ring with a narrow space between the same, the ends of said spaces being closed, a series 85 of narrow recesses extending into the body of the rings from said space, and inlet and exhaust pipes communicating with said space, substantially as described.

2. A boiler comprising inner and outer 90 rings with a narrow space between, means for closing the space at its end, the means at one end being yieldable, recesses in the rings, and inlet and outlet pipes communicating with said space, substantially as described. 95

3. A boiler comprising inner and outer

rings with a space between, means for closing
said space at each end, recesses in the rings,
an inlet-pipe, and overheating-chambers de-
pending axially of the rings within the same,
5 a pipe leading from the space between the
rings to the overheating-chamber and an out-
let-pipe from the overheating-chamber, sub-
stantially as described.

In testimony that I claim the foregoing as
my invention I have signed my name in pres- 10
ence of two subscribing witnesses.

CHARLES ALTMANN.
